REPAIRING LAST

Application filed January 29, 1929. Serial No. 335,882.

The invention relates to a repairing last adapted for use in repairing soles, heels, and other parts of shoes, and particularly high heeled turn shoes, the bottoms of which are thin and liable to be bent out of shape when being tapped and otherwise repaired.

The object of the invention is to provide a repairing last whereby the bottoms of shoes characterized as above stated, may be repaired, without liability of deforming or otherwise injuring the shoe bottom during the repairing operation.

Of the accompanying drawings forming a part of this specification,—

Figure 1 is a top plan view of our improved repairing last.

Figure 2 is a sectional view of the last on line 2—2 of Figure 1, and a side view of the last-supporting means, said figure including a dotted line representation of a shoe in place on the last.

Figure 3 is a section on line 3—3 of Figure 2.

Figure 4 is a section on line 4—4 of Figure 2.

Figure 5 is a section on line 5—5 of Figure 2.

The same reference characters indicate the same parts in all of the figures.

Our improved repairing last, designated as a whole by 10, Figures 3, 4 and 5, is supported by a standard 12, preferably formed with the last and mounted on a base 13, which may be fixed to a bench, or supported by the operator's lap, the standard having a reduced end portion 14, adapted to turn in a socket in the base, a set screw 15 being provided to secure the standard to the base in any position to which it may be turned.

The last is attenuated or slender in cross section, so that a shoe 160, shown by dotted lines, may be easily applied to and removed from it, the length of the last being such that its work-supporting face extends from

the toe to the heel portion of the internal surface of the shoe bottom, as indicated by Figure 2, said supporting face being coextensive in length with the internal surface of the shoe bottom, so that the toe end of said face is adapted to bear on the toe portion of the

shoe upper and the heel end on the heel portion of said upper, as indicated by Figure 2, to prevent endwise movement of the shoe on the last.

The work-supporting face of the last is shaped to conform closely to the fore and heel portions of said internal surface, and to the median line of the shank portion thereof, and includes a fore portion 16, a ball portion 17, a shank portion 18, and a heel seat portion 19. Said face portions 16, 17 and 19 conform closely respectively to the fore portion 20, the ball portion 21, and the heel portion 23 of the internal surface of the shoe bottom, and are coextensive in width with the said bottom portions so that they are adapted to bear on side portions of the shoe upper, as shown by Figures 3 and 5, to prevent side-wise movement of the shoe on the last. The shank portion 18 conforms to the curvature of the longitudinal median line of the shank portion 22 of said internal surface and is narrowed for a purpose hereinafter stated.

The last is particularly adapted to support a high heeled turn shoe during the operations of applying half soles and heels or heel lifts thereto.

The described conformation of the work-supporting face of the last to the internal surface of a turn shoe bottom, and the bearing of said face on the ends and sides of the upper, prevents the possibility of spoiling the shape of the bottom by force applied when the same is being repaired, the bottom of a turn shoe being relatively thin and liable to be bent out of shape, if not adequately supported.

As shown by Figures 2 and 4, the shank portion 18 of the work-supporting face of the last is narrow and formed to support either a wide or a narrow shank portion 22 of the internal face of the shoe bottom, the median line of the fore portion 18 conforming to that of the surface portion 22. The width of the shank portion 22 of a shoe bottom differs in different shoes of the same length and of the same width in the fore and heel parts. The shank portion of the last 18 is narrower than the minimum width of the shank portion 22 of the shoe bottom.

The margin of the heel seat portion 19 is rounded, to conform accurately to the margin of the heel portion 23 of the internal bottom surface, so that there is no liability of breakage of the heel when lifts are being attached thereto.

5 The last is capable of use in the manner described, with only one size of shoe, and is one of a set of preferably five lasts, each of a 10 different size from the others, said lasts being adapted to be used interchangeably with a single base 13.

15 Although our improved last is particularly useful in repairing turn shoes, it may be used, in repairing shoes otherwise made.

18 The form of the side and toe end portions of the fore part of the last is such as to permit repairs of the shoe upper by the application of patches and a cap thereto.

20 A repairing last embodying the invention is characterized chiefly by the fact that the shank or waist of the last is slender and reduced in width, the shank portion 18 of its work supporting face being narrower than 25 the shank portion 22 of the bottom of any shoe for which the last is intended, as indicated by Fig. 4. It will be seen, therefore, that when the last is used in repairing a shoe whose bottom has a shank portion of minimum width, the shank or waist of the last has no injurious bulging contact with the upper at the shank portion of the shoe. In other words the work supporting face of the last conforms closely to the shoe bottom and 30 upper only at the fore and heel portions, as indicated by Figs. 3 and 5, the side portions of the last shank having no close conformation to the upper at the shank portion of the shoe as indicated by Fig. 4.

35 We claim:

40 A repairing last having a shoe bottom supporting face conforming to the length of a shoe of the size or number for which the last is intended; the fore and heel portions of said face conforming in width to the fore and heel 45 portions of the shoe bottom, the shank portion of the last being reduced in width to permit the supporting face portion formed thereon to support either a wide or a narrow 50 shoe bottom shank portion, so that when the last is used in repairing a shoe having a shank portion of minimum width, the shank portion of the last has no injurious contact with the upper at the shank portion of the 55 shoe.

58 In testimony whereof we have affixed our signatures.

JOHN DISCENZA.
JOSEPH FILIPPONE.
